Patented Sept. 7, 1976

241,363

MULTIPURPOSE GAME BOARD

Jean W. Chamberlin, 1340 Placer Ave.,
Ontario, Calif. 91764

Filed May 1, 1975, Ser. No. 573,539

Term of patent 14 years

Int. Cl. D21—01

U.S. Cl. D34—5 SS

Fig. 1

Fig. 2

Fig. 3

Fig. 4

FIG. 1 is a perspective view of a multipurpose game board embodying my new design, showing one side and two edge surfaces thereof;

FIG. 2 is a side elevation thereof, taken from the left side in FIG. 1;

FIG. 3 is a side elevation thereof, taken from the opposite side of FIG. 1; and

FIG. 4 is a bottom plan view thereof.

I claim:

The ornamental design for a multipurpose game board, substantially as shown.
